Patented Nov. 18, 1913.

UNITED STATES PATENT OFFICE.

WILHELM GRAUENFELS AND JOSEF H. GRAUENFELS, OF BUCHAREST, ROUMANIA,
AND DAVID GRAUENFELS, OF BRASSÓ, AUSTRIA-HUNGARY.

GRAIN-SAMPLER.

1,078,847.

Specification of Letters Patent.

Patented Nov. 18, 1913.

Application filed October 30, 1911. Serial No. 657,611.

To all whom it may concern:

Be it known that we, WILHELM GRAUENFELS, JOSEF HEINRICH GRAUENFELS, and DAVID GRAUENFELS, the two former ones 5 subjects of the King of Roumania and the latter of the King of Hungary, and residing the two former ones at Bucharest, Roumania, and the latter at Brassó, Austria-Hungary, have invented certain new and useful Im- 10 provements in Grain-Samplers.

The sampling apparatus for shelled corn according to the present invention comprises substantially two movable tubes, one in the other which are provided with apertures. 15 The latter are, according to the respective position of the tubes, open or closed, and by sinking the tube into the corn the inner tube is filled with corn at different elevations.

In the drawing different forms of devices 20 embodying the invention are shown.

Figure 1 is a side view of the apparatus. Fig. 2 is a vertical section. Fig. 3 is a partial section of the handle. Fig. 4 is a section on line I—II of Fig. 3, the pin *n* being in 25 locking position. Fig. 5 is a section of the connecting parts on an enlarged scale. Fig. 6 shows half of a coupling device of a modified form. Fig. 7 is a side view thereof. Fig. 8 is a section on line V—VI of Fig. 10 30 of the second part of the coupling device. Fig. 9 is a side view of the modification shown in Fig. 8. Fig. 10 is a plan view of the same. Fig. 11 is a section on line III—IV of Fig. 8.

35 The invention comprises a plurality of detachable tubular parts *a*, *a*, *a* which are provided longitudinally with openings *b*. Within each of the sections *a* is fitted with a very small clearance a second tube *f* with 40 a similar opening so that said tube *f* according to its position opens or closes the apertures *b*. The inner tube *f* is provided with a number of partition walls *k* which are dis- 45 posed in such a manner that they form chambers *f'* according to the opening *b*, the upper sides of these walls *k* are inclined, so that the corn may easily run out through the apertures. The lower end *d* of one of the sections *a* terminates in a conical point. 50 Any kind of coupling device may be em- 55 ployed to fit the tubular parts *a*, *a* together.

Fig. 5 shows, by way of example, a device

resembling a screw cap. According to this coupling device, one end of a section *a* is provided with a thread *e'*, while the adjacent 55 end of another section is equipped with a flange *e* which is surrounded by the cap *l*. The different tubular sections can also be connected by the aid of the coupling shown in Figs. 6 to 11, wherein a sleeve *E* surrounds an end of a section *A* which is provided on opposite sides with two depending 60 extensions *K* having slots *K'*, the other end of the tube having a sleeve *E'* which serves to receive the extensions *K* and for this purpose is provided with two longitudinal and vertical recesses *L* and closing springs *M* with noses *N*. On the under smaller part *E''* of the sleeve *E'* is rotatably mounted a ring *O* having on its inner sides eccentric 65 recesses *O'*. Owing to the position of ring *O*, as shown in Figs. 8-11, the noses *N* are ready for coupling and it is sufficient to telescope the tubular part *E*, *E'*, one into the other. If the ring *O* is turned about 90°, the 70 walls of the recesses *O'* press the free ends of the springs *M* inwardly so that the noses *N* in the slots *K'* prevent detachment of the parts *E*, *E'*. The ring *O* is provided, according to Fig. 9, with a horizontal slot *O''* 75 allowing the entrance of a pin *O'''* which arrests the ring in the extreme end positions. When the sections *a*, *a*, *a* are connected it is also necessary to connect the inner tubes *f* 80 in order to guarantee their common rotation. 85 In the present form of embodiments, an end of one of the sections *f* is provided with an angular extension *h*, while the adjacent end of another section has secured thereto a sleeve *i* the bore of which is also polygonal. 90 A handle *S*, having bars *c* is provided which permits of rotation of the tube *f* to the left and of lowering the entire apparatus. The handle can be fitted to each upper coupling half *e'* of the tube *a*, but it 95 must not only permit rotation of the inner tube *f* but also the whole device. In the present form the handle *c* has in its center part a hub *s* which terminates into a polygonal journal *h* and which therefore can be 100 entered in any of the tubes *f* (*A*). In order to prevent the handle *c* from turning within the tube *f*, the upper end of the tube *a*, *f*, the sleeve *i* and the polygonal extension *h*

are provided with corresponding openings m , m' into which can be introduced a pin n . The latter is advantageously attached to the handle c by means of a chain o (Figs. 1, 3 and 4).

The lowest aperture b must be situated quite near the end of the tube a in order to get even samples of corn of the deepest corn layer. In order to prevent the fingers of the 10 user from being pinched when the openings g are closed, the upper part of each tube a is not provided with openings.

The operation is as follows: The apparatus is inserted into the grain while the 15 openings b are closed. The tube f is turned in order to open the chambers k and the apertures b and the sections f and a are then locked in position by introducing the pin n . The apparatus is then rotated with the aid 20 of the handle c so that the chambers f' are filled with corn, the openings b are then again closed, the locking pin n having been

removed from the openings m , m' , and the apparatus withdrawn from the grain.

We claim:

A grain sampler formed of end and intermediate inner and outer sections rotatable upon each other and having registering openings therein, said inner sections having transverse partitions with inclined upper 30 faces, coupling means for detachably connecting the adjacent ends of said sections, means for rotating said inner and outer sections relative to each other, and means for locking said inner and outer sections in fixed 35 position relative to each other.

In testimony whereof, we have hereunto set our hands in presence of two witnesses.

WILHELM GRAUENFELS.

J. H. GRAUENFELS.

DAVID GRAUENFELS.

Witnesses:

OSKAR DURR,

H. NOLFFNER.
